UNITED STATES PATENT OFFICE.

VALENTIN JAKOB ODHNER, OF STOCKHOLM, SWEDEN.

CALCULATING MACHINE.

Application filed November 2, 1922. Serial No. 593,621.

To all whom it may concern:

Be it known that I, VALENTIN JAKOB ODHNER, a subject of the King of Sweden, and resident of Vikingagatan 30, Stockholm, 5 in the Kingdom of Sweden, have invented certain new and useful Improvements in Calculating Machines, of which the following is a specification, reference being had therein to the accompanying drawings.

10 This invention relates to improvements in calculating machines of that class which are provided with a number of turnable calculating discs in which are arranged adjustable ten's-, hundred's-, etc. pins, which in active position by the turning of the calculating discs catch into the respective toothed wheel or the like for the adjustment of the indicating discs of the machine. In calculating machines of this class the ten's-pins 15 etc. are as known brought back into inactive position by springs or the like, acting on the pins and likewise designed to keep the pins in inactive position. By said means the bringing back of the pin is exclusively dependent on the spring, which of course is unreliable, because it may happen, particularly in machines which have been used for a long time, that the spring by one reason or another is incapable of bringing back the 20 pin into inactive position before this, during the rapid turning of the calculating discs, again is at the toothed wheel in question, which thus may be unintendedly moved. The arrangement is especially unsuited to 25 calculating machines of that class which are provided with two registers situated next to each other and acting with the same calculating discs, on account of the fact that one is forced to make the diameter of the calculating discs comparatively large in order to diminish the risk of said unintended movement, so that the two toothed wheels of the machine next to each calculating disc with which the teeth are intended 30 to cooperate, may be arranged at such a distance from each other, that the spring at least theoretically may be capable of bringing back the pin into inactive position during the passing between the toothed wheels.

According to this invention, the object 35 is to eliminate said inconveniences, and the machine is provided with immovable parts, which are provided with guides, cams or shoulders, which are intended to cooperate 40 with the ten's-pin in question for the fore-

ing back of the latter into inactive position, after the pin has turned the toothed wheel one step.

In the accompanying drawings are shown some embodiments of the invention applied to calculating machines provided with ten's-hundred's- etc. pins adjustable in various ways. Fig. 1 shows the invention applied to a calculating machine with ten's-pins etc. swingable transversally to the calculating disc. Fig. 2 is a section in larger scale on the line 2—2 of Fig. 1. Fig. 3 shows the invention applied to a calculating machine with ten's-pins etc. swingable in the plane of the calculating disc. Fig. 4 is a section 65 in larger scale on the line 4—4 of Fig. 3. The Figs. 5 and 6 show another embodiment of the invention, the parts being in different positions, the embodiment being applied to a calculating machine in which the 70 ten's-pins etc. are swingable in the plane of the calculating discs, the ten's-pins etc. being combined with a known swingable shutter or the like intended to close or liberate an opening for a star wheel during the 75 movement of the pin. Fig. 7 is a section in larger scale on line 7—7 of Fig. 5. Of the calculating machine; only those parts are shown which are necessary for the explaining of the invention. 85

On a shaft 2 turnably mounted in the frame 1 of the machine calculating discs—of which only one is shown in the drawing—are arranged next to each other as usual. Each calculating disc 3 (with the exception of the calculating disc for the units) is provided with two ten's- hundred's- etc. pins 4 adjustable by known means of which pins one is intended to be active during multiplying and adding and the other is intended to be active during division and subtraction. In order to bring the ten's-pins 4 etc. into active position, so called ten's-transferring arms 6 are swingably mounted in the displaceable carriage 5 which arms 90 act in the usual manner. During the turning of the calculating discs the pin 4 being brought into active position catches into an intermediate toothed wheel 7 and turns this one step. The intermediate wheel 7 95 gears into a registering wheel 8, which is fastened to a numbered disc. 100

According to Figs. 1 and 2 each ten's-pin 4 etc. is swingable transversally to the calculating disc and is acted upon as usual 110

by a spring, not shown, which tends to move the pin in the direction indicated by the arrow 9 in Fig. 2. In the carriage, a part 10 is arranged for each calculating disk, which 5 (with the exception of the calculating disk for the units) are provided with two of the tens-pins etc. cooperating with guiding surfaces 11, 12 one of which is acting during adding and multiplying and the other of 10 which is acting during subtraction and division. According to Fig. 2 the pin 4 is brought into active position by the transferring arm 6 and catches into the intermediate wheel 7. By the turning of the calculating discs in the direction of the arrow the pin abuts against the guiding surface 11, so that it will be forced back into the inactive position shown by the dot—dash—lines immediately after its having 15 turned the toothed wheel one step. As may be seen in Fig. 2 the part 10 is situated so that the teeth 4 in inactive position freely can pass it during the turning of the calculating discs.

20 In Figs. 3 and 4 is shown an embodiment applied to a calculating machine, which is provided with ten's-pins etc. swingable on pivots 15^a in the plane of the calculating discs, the cams or guiding surfaces 11, 12 of 25 the part 10 thereby are intended to act on parts attached to the ten's-pins. The pin 4, which as usual is acted upon by a spring, is in a known way fastened to an arm 13 or the like swingable about the axis 15^a, 30 which for the sake of bringing back the pin into active position is intended to be acted upon by the transferring arm 6. In the calculating disc 3 is turnably arranged at each ten's pin etc. a part in the form of an 35 arm 14 pivoted at 14^a, which is attached to 40 the pin or to an arm 15, connected with the pin and acting as a lever. From Fig. 3 it may be seen that when the lever or arm 14 is in the full line position, that its slot 17 45 engages the pin 16 in such manner that the member 15 is held in the position shown in this figure, so that the pins 4 and 13 which move with the member 15 are in the position shown. Now if the lever 14 is moved in a 50 clockwise direction about its pivot 14^a, the pin 16, which is attached to the part 15, will ride toward the inner end of the slot 17 and will thus cause the member 15 to swing about the pivot 15^a and cause the pin 14 to 55 project beyond the periphery of the disk 3. From Fig. 4 it may be seen that the parts 4, 13, 14 and 15 lie in different planes parallel to the disk 3. According to the drawing the 60 arm 15 is provided with a pin 16, which is movable in a groove 17 in the arm 14. When the pin 4 is in the inactive position, shown in Fig. 3 the arm 14 lies out of catching position for the part 10, but when the pin 4 by the acting of the transferring arm 6 on the 65 arm 13 is brought into active position the

arm 14 is swung into the position shown in Fig. 3 by dot—dash—lines. After the turning one step of the intermediate wheel 7 by the pin during the turning of the calculating discs in the direction shown by the arrow the arm 14 abuts against the cam or shoulder surface 12, whereby the arm and the pin 4 are brought back into their inactive positions.

In the Figs. 5—7 is shown another embodiment of the invention applied to a calculating machine with ten's-pins, which are acted upon by springs, and which are provided with arms 13 which may be acted upon by the transferring arm 6 as in Figs. 75 3 and 4. The pin 4 is combined in known manner with a swingable shutter 18 or the like, which as usual is arranged for the shutting during the inactive position of the pin (Fig. 3) of an opening 19 in the calculating disc, the opening 19 being made for a star-wheel, not shown in the drawings, but which shutter by the bringing of the pin into active position is swung back from the opening, so that the star-wheel is able to be 80 turned one step, Fig. 6. Each of the shutters 18 is provided with an arm 20, which is intended to cooperate with the cam surface 11 or 12 for the forcing back of the pin into inactive position, when it during the 85 turning of the calculating discs, has turned the intermediate wheel 7 one step.

As may be seen from Figs. 5 and 7, the pins or arms 4 and 13 form a fork-shaped lever pivoted on the axis 4^a and the two 90 arms are in different parallel planes. The arm 13 carries a pin 18^a which projects outwardly through the opening 19 and rides in a slot 13^b in the member 18 which is pivotally mounted at 18^a on one side of the disk 100 3. When the parts are in the position shown in Fig. 5, the pin 4 lies within the circumference of the disk 3 and is inactive. When, however, the arm 13 is struck, the pin 4 will be moved outwardly to the position 105 shown in Fig. 6 and then it will function to move the toothed wheel 7 one step in a manner similar to that described in connection with Figs. 1 to 4 inclusive.

The construction shown in Figs. 3, 4, 5, 6 110 and 7 requires a right and left hand construction for addition and subtraction.

The arrangement, small alterations being made, may be applied to all kinds of adjustable ten's pins in calculating machines of 115 this class. The shown embodiments are only to be considered as examples for the explaining of the invention.

Having now described my invention, what I claim as new and desire to secure by Letters Patent is:

1. A transfer mechanism for calculating machines including pin wheels, an immovable shaft, adjustable ten's transferring members mounted on said shaft, adjustable trans-

fer actuating pins located in the pin wheels and brought into active position by means of said adjustable ten's transferring members, toothed wheels engaged by said pins 5 during the rotation of the pin wheels, numeral wheels actuated by said toothed wheels, each transfer actuating pin being provided with an element adapted to contact with fixed members arranged outside of 10 the periphery of the pin wheels and provided with guiding shoulders adapted to cooperate with said elements for forcing the pin into inactive position after it has turned its corresponding toothed wheel one step.

15 2. A transfer mechanism as claimed in claim 1 in which the transfer actuating pin is movable in the plane of the pin wheel.

3. A transfer mechanism as claimed in claim 1 in which the element of each transfer actuating pin is movable relatively to 20 the pin with which it is associated.

4. A transfer mechanism for calculating machines including pin wheels, a pin movably mounted on each wheel, a toothed wheel arranged adjacent each pin wheel, the pin 25 in its inactive position being capable of passing by the toothed wheel without actuating the latter, an adjustable ten's transferring member for moving the pin into a position to engage the toothed wheel when 30 the pin wheel is actuated, stationary cam surfaces so arranged relatively to each pin wheel and toothed wheel as to force back the pin into inactive position after it has turned the toothed wheel one step, and a 35 numeral wheel actuated by the toothed wheel.

In witness whereof I have hereunto signed my name.

VALENTIN JAKOB ODHNER.
